CLAIM

The ornamental design for a respirator inlet port connection seal, as shown and described.

DESCRIPTION

FIG. 1 is a front perspective view showing a new design for a respirator inlet port connection seal;

FIG. 2 is a front view thereof;

FIG. 3 is a side view thereof;

FIG. 4 is a back view thereof;

FIG. 5 is a second side view thereof;

FIG. 6 is a top view thereof; and,

FIG. 7 is a bottom view thereof.

The broken lines shown in the drawings show unclaimed features of the respirator inlet port connection seal and form no part of the claimed design. The dot-dash broken lines form a boundary of the claimed design and do not form a part of the claimed design.
